CLAIM

The ornamental design for a clasp, as shown and described.

DESCRIPTION

FIG. 1 is a front perspective view of a clasp, in accordance with our design;

FIG. 2 is a rear perspective view of the clasp of FIG. 1;

FIG. 3 is a left side view of the clasp of FIG. 1;

FIG. 4 is a right side view of the clasp of FIG. 1;

FIG. 5 is a front view of the clasp of FIG. 1;

FIG. 6 is a rear view of the clasp of FIG. 1;

FIG. 7 is a bottom view of the clasp of FIG. 1;

FIG. 8 is a top view of the clasp of FIG. 1;

FIG. 9 is front perspective view of the clasp of FIG. 1 with environmental subject matter; and,

FIG. 10 is a disassembled view of the clasp of FIG. 1.

The broken lines in FIG. 9 show environmental structure and form no part of the design. The portions of the clasp shown in broken lines form no part of the claimed design.

1 Claim, 4 Drawing Sheets
